ATTORNEY.

UNITED STATES PATENT OFFICE.

JAMES BROWN, OF PAWTUCKET, RHODE ISLAND.

PUZZLE.

Application filed May 22, 1922, Serial No. 562,613. Renewed February 12, 1925.

To all whom it may concern:

Be it known that I, JAMES BROWN, a citizen of the United States, residing at 176 Mагill Street, Pawtucket, in the county of 5 Providence and State of Rhode Island, have invented certain new and useful Improvements in Puzzles, of which the following is a specification.

My invention consists of a puzzle comprising a number of cards or plates of modified hexagonal form bearing upon their margins certain names or characters, said plates being capable of being assembled in such a manner that the marginal names 10 upon contiguous tablets will be the same, the entire combination when completed forming a symmetrical figure. In the particular puzzle shown in the drawings, I have used for the marginal names the titles of various 15 colleges throughout the United States, but any other names, symbols or characters may be used and I have also indicated the respective colors of the various colleges upon the hexagonal units forming the puzzle.

20 My invention is disclosed in the accompanying drawing, in which

Figure 1 shows the completed puzzle, and Figure 2 shows the separated unit thereof.

As shown in the drawings, the units consist of modified hexagons, the sides thereof 30 being alternately concave and convex, of the same curvature so as to fit together, as shown in Figure 1.

Upon each margin is indicated the name 35 of a college, Yale, Princeton, and the like, with its color indicated on the segment adjacent to the name.

The solution of the puzzle consists in so arranging the various units that when they 40 are all assembled the name of each college upon one unit will be adjacent to the same name upon the contiguous unit, the entire combination forming a symmetrical figure, as shown in Figure 1.

45 It will be seen that this puzzle is not limited to the actual number of units disclosed in Figure 1, but the number may be increased from a minimum of seven to any maximum desired.

50 An inspection of the several units will

disclose that the sequence of names upon any single unit is different from those of every other unit within the limitation of the possible combinations of these separate names, and it is this element that renders this puzzle one of considerable difficulty and which requires for its solution a great deal of patience.

The coloring of the various segments is, of course, unimportant, the essential element 55 being the modified hexagonal form with the varying arrangements of names upon the margins.

Having now described my invention, what I claim and desire to secure by Letters 60 Patent is—

1. A puzzle comprising a plurality of units, each of identical configuration and having alternate convex and concave edge surfaces, each unit having a plurality of 70 substantially triangular color configurations on the face thereof with a color configuration disposed adjacent each curved edge of the unit, the convex edge of one unit registering with the concave edge of another unit 75 with similar color configurations adjacently positioned.

2. A puzzle comprising a plurality of units, each of identical configuration and having alternate convex and concave edge 80 surfaces, each unit having a plurality of substantially triangular color configurations on the face thereof with a color configuration disposed adjacent each curved edge of the unit, the convex edge of one unit registering with the concave edge of another unit 85 with similar color configurations adjacently positioned, the color configurations adjacent the convex edges of the unit being of lesser area than the other configurations 90 with similar color configurations of different areas positioned when the units are assembled.

In testimony whereof I affix my signature in presence of two witnesses.

JAMES BROWN.
